[57] **CLAIM**

The ornamental design for paneling for a kitchen cabinet or similar article, substantially as shown and described.

DESCRIPTION

FIG. 1 is a perspective view of one form of panel.

FIG. 2 is a front view of a similar panel.

FIG. 3 is a front view of another panel.

FIG. 4 is a partial and broken away view of the panel shown in FIGS. 1 to 3, and particularly showing a perspective view of the handle.

FIG. 5 is a partial sectional view of the panel taken along the longitudinal bisecting plane I—I in FIG. 4, and particularly showing a longitudinal bisecting view of the handle.

The dominant features of the design reside in the portions shown in full line.

FIG. 1

FIG. 2

FIG. 3
